GROUPING MECHANISM FOR VOTING-MACHINES.

No. 832,014.

Specification of Letters Patent.

Patented Sept. 25, 1906.

Application filed October 31, 1905. Serial No. 285,233.

To all whom it may concern:

Be it known that I, WILLIAM I. T. FOSDICK, a citizen of the United States, residing at Bridgeport, county of Fairfield, State of Connecticut, have invented a new and useful Grouping Mechanism for Voting-Machines, of which the following is a specification.

This invention relates to that portion of the mechanism of a voting-machine that has to do with "group voting," so called. The term "group voting" is used as broadly descriptive of a style of voting which permits voters to vote for more than one candidate for the same office—as, for example, in voting for a plurality of members of a board, commission, court, or a delegation of two or more members. Suppose, as an illustration, that three justices of the supreme court are to be elected and that the several parties have each made three nominations for that office.

The invention is shown as applied to a machine in which the names of party-candidates are placed in vertical columns, and the names of all candidates for the same office are placed in horizontal lines, the name of each candidate being in its proper party-column. The machine is provided with horizontally-placed chains corresponding with the horizontal lines of names of candidates, the act of voting being performed by movement of voting members which when actuated produce a bend or slack in the chain, each chain being tightened up so as to have but one slack in it, thus making it normally impossible for a voter to vote for but one candidate for any office. In the present instance I have shown the act of voting as performed by means of voting-shafts which when oscillated cause corresponding locking-dogs to press upon the chains and make a bend or slack therein. I shall not describe the voting mechanism in detail, however, for the reason that it forms no portion of the present invention.

The present invention consists in certain constructions and in certain parts, improvements, and combinations to adapt a voting-machine for group voting, which permit groups of chains to be so connected up as to permit a number of votes corresponding with the number of chains in the group to be cast in accordance with the will of the voter, all in one line or in different lines, as preferred, it being impossible, however, for the voter to

cast but one vote for any candidate or more votes for the office than there are chains in the group.

In the accompanying drawings, forming a part of this specification, in which reference characters are used to indicate the several parts, Figure 1, is a detail elevation illustrating the construction and operation of my novel grouping mechanism; Fig. 2, an enlarged detail sectional view on the line 2 2 in Figs. 1 and 4; Fig. 3, a similar section on the line 3 3 in Figs. 1 and 4; Fig. 4, an enlarged detail rear elevation, and Fig. 5 is an enlarged detail elevation corresponding with Fig. 1, illustrating a slightly-variant form of grouping-plates and mode of attachment.

10 denotes one of the end standards of a voting-machine; 11, the chains; 12, voting-shafts, and 13 locking-dogs carried by the voting-shafts, which engage the chains in the act of voting. The right end of each chain is fixed in any suitable manner, which forms no portion of the present invention. The left end of each chain is provided with a threaded shank 14, which passes through an opening in an arm 15, extending from a plate 16, the adjustment of the chains being regulated by 75 nuts 17, which engage the threaded shanks and also engage the opposite sides of arms 15.

18 denotes links, one end of each link being pivoted to a plate 16 and the other to a holding-plate 19. These holding-plates and the 85 grouping-plates (indicated by 20) lie in a vertical groove 21, which may be formed in the standard or in a plate 28, which is secured to the standard by screws 29.

22 denotes a covering-plate which is secured to plate 28 and retains the holding-plates and grouping-plates in place in the groove, but without interfering with their freedom of movement.

The holding-plates are shown as angular in 95 configuration and the grouping-plates as angular in Figs. 1 and 4 and as disk-shaped in Fig. 5, so as to present curved bearing-surfaces to the holding-plates. This is an unimportant detail of construction, it being 100 simply required that the holding-plates and grouping-plates be so shaped as to engage and slide freely on each other, as will be more fully explained. The holding-plates are shown as provided in their under sides with 105 recesses 23 to receive the ends of the links.

and the grouping-plates are shown as provided in their under sides with recesses 24 to permit the links to oscillate freely. Each holding-plate, except those at the ends of the 5 vertical column, lies between two grouping-plates, which are normally locked in position by keys 25, which lie in sockets in the grouping-plates, pass through the grouping-plates, and engage either plate 28, as shown in Fig. 3, 10 or the standard should plate 28 be dispensed with. If preferred, the grouping-plates may be locked by screws 26 engaging plate 28, as shown in Fig. 5, or the standard. The holding-plates normally have slight movement— 15 that is to say, they are not held rigidly by the grouping-plates, as is indicated in Fig. 1.

27 denotes lugs, one lying in front of each grouping-plate to retain it in the groove when the locking key or screw is removed.

20 In normal voting the grouping-plates are all fixed in place, each chain being so adjusted in setting up the machine as to permit the actuation of a single voting member, as indicated in Fig. 1 in connection with the fifth to 25 the ninth chains, inclusive, one voting member having been actuated in each of the corresponding horizontal lines.

The operation of setting up the machine for group voting is illustrated by means of 30 the first, second, and third chains in Fig. 1. It consists simply in removing certain of the keys or screws which lock the grouping-plates, leaving the grouping-plates free to move laterally, the covering-plate being first 35 removed and then replaced after the grouping-plates have been released. In the present instance the first, second, and third chains have been released for group-voting. The keys which lock the first and second 40 grouping-plates have been removed, leaving them free to move laterally and permit longitudinal movement of the holding-plates to which the grouped chains are attached, so that the slacks may be shifted from one 45 chain to another. In the present instance there are three candidates, three grouped chains, and of course three slacks. The requirement is to place one, two, or three slacks in either of the chains; but it is im- 50 possible to place more than three slacks anywhere. By removing the keys which lock the two corresponding grouping-plates said grouping-plates are permitted to slide laterally and increased longitudinal movement is 55 given to the holding-plates to permit either one or two additional slacks to be placed in either of the chains. Should the voter desire to vote for one candidate in each of the horizontal lines corresponding with the three 60 grouped chains, the operation would be normal and there would be no lateral movement of the released grouping-plates. As illustrated in Fig. 1, however, the voter has elected to 65 vote for three candidates in the second horizontal line and has actuated three voting

members in that horizontal line. The effect has been to take the slacks out of the first and third chains and transfer them to the second chain, which now has three slacks, two in addition to its normal slack. This result has been effected by the action of the three voting members; which in putting the three slacks into the second chain have drawn the holding-plate of the second chain forward to the limit of its movement. This movement of 75 the second holding-plate, through the engagement of said holding-plate with the first and second grouping-plates, has moved said grouping-plates laterally in opposite directions, which in turn have forced the first and third holding-plates backward to the limit of their movement, so that the first and third chains will be perfectly taut and the slacks of the three chains will all be placed in the second chain. Should the voter prefer, he 80 might vote for two candidates in either of the three horizontal lines of names of candidates and one in either of the other lines or for one in each of the lines. In other words, the voter might vote for any one, two, or three of 85 the candidates nominated in either of said three horizontal lines of names of candidates, but could only vote for three candidates under any circumstances. The same principle of 90 operation and mode of setting up the machine 95 is applicable where two, four, five, or more candidates are to be voted for in a group within the limits of the machine. Should two chains only be grouped, one grouping-plate only would be released, which of course 100 would be the grouping-plate lying between the holding-plates of the two chains that were to be grouped. Should four chains be grouped, three grouping-plates would be released. Should five chains be grouped, four 105 grouping-plates would be released, and so on.

Having thus described my invention, I claim—

1. In a mechanism of the character described, the combination with a plurality of 110 chains and holding-plates to which the chains are respectively connected at one end, the other ends being fixed, of laterally-movable grouping-plates lying between the holding-plates, the said chains being mounted to 115 have a predetermined amount of slack.

2. In a mechanism of the character described, the combination with a plurality of 120 chains and holding-plates to which the chains are respectively connected at one end, the other ends being fixed, of laterally-movable grouping-plates lying between the holding-plates, and means for locking the grouping-plates when the machine is being used for 125 other than group-voting, the said chains being mounted to have a predetermined amount of slack.

3. In a mechanism of the character described, the combination with a plurality of 130 chains, holding-plates to which the chains

are respectively connected at one end, the other ends being fixed, and laterally-movable grouping-plates lying between the holding-plates, of a plate provided with a longitudinal groove to receive the holding-plates and grouping-plates and means for retaining said holding-plates and grouping-plates in the groove without interfering with their freedom of movement, the said chains being mounted to have a predetermined amount of slack.

4. In a mechanism of the character described, the combination with a plurality of chains, threaded shanks at the ends of the chains and plates 16 provided with arms to which the shanks are adjustably secured, of holding-plates, links connecting plates 16 to the holding-plates respectively, and laterally-movable grouping-plates lying between the holding-plates, the said chains being mounted to have a predetermined amount of slack.

5. In a mechanism of the character described, the combination with a plurality of chains, and angular holding-plates to which the chains are respectively connected at one end, the other ends being fixed, of correspondingly-shaped laterally-movable grouping-plates lying between the holding-plates, the said chains being mounted to have a predetermined amount of slack.

6. In a mechanism of the character described, the combination with a plurality of chains, and holding-plates having recesses in their under sides in which the ends of the chains are pivotally secured, of laterally-movable grouping-plates lying between the holding-plates, the said chains being mounted to have a predetermined amount of slack.

7. In a mechanism of the character described, the combination with a plurality of chains, and holding-plates to which the

chains are pivotally connected at one end, the other ends being fixed, of laterally-movable grouping-plates lying between the holding-plates and means for retaining the holding and grouping plates in place without interfering with their freedom of movement, the said chains being mounted to have a predetermined amount of slack.

8. In a mechanism of the character described, the combination with a plurality of chains, holding-plates to which the chains are pivotally connected at one end, the other ends being fixed, and laterally-movable grouping-plates lying between the holding-plates, of a plate 28 having a groove to receive the holding and grouping-plates, lugs on said plate for retaining the grouping-plates in the groove, and a covering-plate secured to plate 28 by which the holding-plates and grouping-plates are retained in place without interfering with their freedom of movement, the said chains being mounted to have a predetermined amount of slack.

9. In a mechanism of the character described, the combination with a plurality of chains each having at its end a threaded shank, plates 16 having arms through which the shanks pass, nuts on opposite sides of said arms whereby the shanks are adjustably secured thereto, of holding-plates, links by which plates 16 are connected to the holding-plates and laterally-movable grouping-plates lying between the holding-plates, the said chains being mounted to have a predetermined amount of slack.

In testimony whereof I affix my signature in presence of two witnesses.

WILLIAM I. T. FOSDICK.
